Primary Examiner — Mary Ann Calabrese(74) *Attorney, Agent, or Firm* — Michael J. Brown(57) **CLAIM**

I claim the ornamental design for the seating unit, as shown and described.

DESCRIPTION

FIG. 1 is a rear view of a seating unit showing my new design.

FIG. 2 is a top side view thereof.

FIG. 3 is a front view thereof.

FIG. 4 is a bottom thereof.

FIG. 5 is a front perspective view thereof.

FIG. 6 is a rear view of the new ornamental seating unit of the present invention.

FIG. 7 is a top side view thereof.

FIG. 8 is a front view thereof.

FIG. 9 is a bottom thereof.

FIG. 10 is a front perspective view thereof; and,

FIG. 11 is a left side view of the present invention, the right side view being a mirror image thereof.

The broken lines in the drawings are for the purpose of illustrating portions of the seating unit that form no part of the claimed design.
